UNITED STATES PATENT OFFICE.

HARRY SHEPHERD AND DENNIE DELARIA, OF MINNEAPOLIS, MINNESOTA.

HOSE-CO尤LING FOR AIR-BRAKES.

SPECIFICATION forming part of Letters Patent No. 635,402, dated October 24, 1899.

Application filed April 6, 1899. Serial No. 711,965. (No model.)

To all whom it may concern:

Be it known that we, HARRY SHEPHERD and DENNIE DELARIA, citizens of the United States, residing at Minneapolis, in the county 5 of Hennepin and State of Minnesota, have invented a new and useful Improvement in Hose-Couplings for Air-Brakes, of which the following is a full, clear, and exact description, reference being had to the accompanying 10 drawings, which form a part of this specification.

The purpose of our invention is to provide means for automatically closing the air-passages in hose-couplings when the same are disconnected, thereby preventing sand or dust 15 from lodging therein.

The principle of construction as applied to the air-brakes now in use is so well understood that we do not deem it necessary to describe it herein further than to say that when the pipes which carry the compressed air from one car to another throughout the length of the train are "broken" (uncoupled) their open 20 ends rest near the ground and that sand and dust accumulate therein, often to the extent of clogging the screens with which the compression-cylinders are provided, thereby preventing the operation of the triple valves located therein, and as the brakes are set 25 through the operation of the said triple valves collisions too frequently occur, and it is the purpose of our invention to so effectually exclude the sand and dust from the said pipes and cylinders as to render accidents from such 30 cause exceedingly infrequent, if not impossible. At the same time we provide for the free passage of the compressed air in the pipes and cylinders when the couplers are connected and for the release of the same 35 40 therefrom when the couplers are disconnected or when the pipes are broken. To this end our invention consists in providing hose-couplings with valves of peculiar construction, which valves are herein clearly shown and 45 hereinafter fully described.

In the accompanying drawings, Figure 1 is a top view of our coupler as it appears when in use; Fig. 2, a side elevation of the same; Fig. 3, a side elevation thereof as it appears 50 when in position to be disconnected; Fig. 4, a side elevation of one-half of the coupler detached from its fellow, showing the opening

therein; Fig. 5, a bottom view of the same; Fig. 6, a section of Fig. 1, taken on the line 6 6, showing side elevation of the valves; 55 Figs. 7 and 8, sectional views of the valve in different positions, and Fig. 9 a detail.

Similar letters refer to similar parts throughout the several views.

A is the coupler, and B the valve. The 60 coupler, as before stated, is not unlike those commonly used. It consists of two parts, each part being hollow and each being provided with a side and an end opening, thus 65 providing for a free passage of the compressed air into and through one and out from the other. The head portion of each half-coupler is provided with an interlocking clutch *a* and lug *b*, which when engaged hold them firmly together. The stop-pin *c* serves to 70 regulate or limit the movement of one half-coupler with or upon the other. The side opening *d* of each half-coupler A is provided with a recessed bushing *e*, which renders the joint effected by their union air-tight. As 75 thus described, the coupler is substantially like those commonly used, and our improvement consists in affixing in the head portion of each half-coupler the valve herein shown and described. As a practical way of accomplishing this we pierce the concavo-convex side of the half-couplers and affix therein the pin *f*. This pin serves as the valve-guide, over which we slide the coiled spring *g*. Over the stem *f* and onto the spring *g* we now force 80 the valve B, an end view of which is shown in detail Fig. 9. This valve B consists of a longitudinally-pierced shaft portion *h*, with a spider-head flange *i* at one end and a flanged head *j* at the other. Onto this shaft portion *h* 85 is mounted a longitudinally-shifting portion *k*, (the valve proper,) consisting of a centrally-pierced and circumferentially-grooved flange having the circumferentially-recessed packing *l* therein. Between this movable flange *k* and the head *j* is a coiled spring *m*, the purpose 90 of which is to hold the movable flange *k* (the valve) up to or against its seat *i* (the spider-head flange.) Now it will be seen that when the two halves of the coupler A are brought into 95 contact the flanged heads *j* of the valve B will first contact and the valves will be forced from each other into the heads of the couplers, as shown in Fig. 6, where they will be held open so

long as they remain connected, thus providing a free passage for the compressed air from one half of the coupler to the other, and consequently throughout the length of the train, 5 and that when the two halves of the coupler A are disconnected the valves B will be forced outward by the reflex action of the springs *g* until they are seated, (the position shown in Fig. 7,) when the compressed air in the pipes 10 passing through the spider-head flange *i* will depress the springs *m* and force the movable flange *k* outward, as shown in Fig. 8, where they will be held until the air in the pipes shall have reached its normal density, when 15 through the reflex action of the spring *m* they will be forced back to their seats, as shown in Fig. 7, where they serve to close the opening *d* of the couplers A, the outer circumferential walls of their packing-rings *l* 20 contacting with the inner circumferential wall of the bushings *e*, effectually closing the openings *d* and excluding the sand and dust therefrom. Thus the purposes of our invention are accomplished. 25 Having thus described our invention, what we claim as new, and desire to secure by Letters Patent, is—

1. The combination with hose-couplers of the character described, of centrally-pierced 30 valves, mounted and longitudinally movable

upon pins affixed in the said couplers, said valves being seated, and held in place closed, by means of springs affixed thereto, and deflected by contact with, and held in place open, by connecting the said couplers, all 35 substantially as shown and for the purposes specified.

2. The combination with hose-couplings of the character described, of pins laterally affixed therein, centrally-pierced valves mounted, and longitudinally movable upon the said pins, and springs for holding the said valves seated when the said hose are disconnected substantially as shown and for the purposes specified. 40

3. In a hose-coupler of the character herein described, the combination therewith of a pin laterally affixed in its interior wall, a centrally-pierced, longitudinally-movable valve mounted thereon, a spring inclosing said pin 50 and back of said valve, a flange, longitudinally movable upon the shaft portion of the said valve and a spring in front of said flange, all substantially as shown and for the purposes specified. 45

HARRY SHEPHERD.
DENNIE DELARIA.
